190,003

CARGO AIRPLANE OR THE LIKE

Lincoln B. Wiley, Hawthorne, Calif., assignor to Doak
Aircraft Co., Inc., Torrance, Calif., a corporation of
California

Filed Apr. 13, 1959, Ser. No. 55,482

Term of patent 14 years

(Cl. D71—1)

FIG. 1.

FIG. 2.

FIG. 3.

*FIG. 4.**FIG. 5.*Fig. 1 is a front elevational view of a cargo airplane showing my new design;

Fig. 2 is a side elevational view thereof;

Fig. 3 is a plan view taken from the top thereof;

Fig. 4 is an enlarged, rear elevational view of a thrust-generating unit on the extremity of the wing thereof; and

Fig. 5 is an enlarged rear elevational view of a thrust-generating unit on the tail thereof.

I claim:

The ornamental design for a cargo airplane or the like, as shown.
